DESIGN FOR A DIE-CASTING MACHINE

Aubrey Robert Mills, Southgate, England

Application May 25, 1945, Serial No. 119,723

Term of patent 14 years

(Cl. D55—1)

To all whom it may concern:

Be it known that I, Aubrey Robert Mills, a subject of the King of Great Britain, residing at Southgate, England, have invented a new, original, and ornamental Design for a Die-Casting Machine, of which the following is a specification, reference being had to the accompanying drawing, forming part hereof, in which:

Fig. 1 is a perspective view showing the top,

front and one end of a die-casting machine embodying my new design; and

Fig. 2 is a perspective view showing the top, rear and other end thereof on a slightly reduced scale.

I claim:

The ornamental design for a die-casting machine, as shown.

AUBREY ROBERT MILLS.
